(57) **CLAIM**

The ornamental design for a sensor soap dispenser, as shown and described.

DESCRIPTION

FIG. 1 is a front view of the sensor soap dispenser showing my new design;

FIG. 2 is a back view thereof;

FIG. 3 is a left side view thereof;

FIG. 4 is a right side view thereof;

FIG. 5 is a bottom view thereof;

FIG. 6 is a perspective view thereof; and,

FIG. 7 is another perspective view thereof.
